UNITED STATES PATENT OFFICE.

ANDREW SMITH, OF CHICAGO, ILLINOIS, ASSIGNOR TO HALSAM PRODUCTS COMPANY, OF CHICAGO, ILLINOIS, A CORPORATION OF ILLINOIS.

METHOD OF AND APPARATUS FOR ELIMINATING SHARP EDGES AND CORNERS ON TOY BLOCKS.

Application filed June 14, 1920. Serial No. 388,842.

To all whom it may concern:

Be it known that I, ANDREW SMITH, a citizen of the United States, residing at Chicago, in the county of Cook and State of Illinois, have invented certain new and useful Improvements in Methods of and Apparatus for Eliminating Sharp Edges and Corners on Toy Blocks, of which the following is a specification.

10 My invention relates to method of and apparatus for eliminating sharp edges and corners on toy blocks more particularly to wood blocks of prismatic shape, for example of the shape of a cube. The wood in 15 the rough is first put through certain preliminary sawing and planing operations, whereby a strip having its four straight grained or longitudinal edges rounded is obtained, the strips being substantially square in cross-section except for the rounded edges, if cubical blocks are to be made. These strips are then sent to a gang saw and cut into blocks. The fuzz due to sawing operation is then removed, which may be done in several ways, 20 for example, by tumbling the blocks for a few minutes in a revolving container.

One of the objects of the invention is to provide a novel method of eliminating the sharp edges and corners on the blocks after 25 they have been passed through the preliminary operations mentioned, which preferably consists in passing the blocks successively through sets of rollers adapted to bear upon the edges thereof, the plane of each successive set being substantially at right angles to that of the preceding set of rollers, thereby compressing and rounding the eight cross grained or transverse sharp edges, also to a certain extent the corners, and then gripping 30 and squeezing the eight corners of the block between suitable dies to further round the same. While I prefer, as a matter of economy in manufacturing, to eliminate the sharp longitudinal or straight grained edges 35 of the blocks during said preliminary operations, it will be understood that these sharp edges may also be eliminated by the method mentioned by passing the blocks through an additional set of rollers.

40 A further object of my invention is to provide novel apparatus for carrying out the various steps of the method mentioned whereby large quantities of the finished blocks may be turned out in a relatively

short period of time and with a minimum 55 amount of labor.

Further objects of the invention are to provide automatic means for carrying and guiding the blocks through the various sets of rollers and into position between the 60 dies for further rounding the corners and to provide means whereby the relative positions of the rollers and the guiding elements may be changed to accommodate the apparatus to blocks of different size.

65 I have also discovered that the sharp edges and corners on a block of the class described may be eliminated by positioning the block between suitable dies and then gripping and squeezing the edges and corners thereof 70 whereby the same are compressed and rounded. Preferably the longitudinal or straight grain sharp edges are eliminated by passing the block through the preliminary operations mentioned. Certain of the appended 75 claims cover the method of and apparatus for eliminating the sharp edges and corners in this manner.

The invention consists in the novel methods to be hereinafter described and 80 claimed for eliminating the sharp edges and corners on a block of the class described and in the novel constructions, arrangements and devices, to be hereinafter described and claimed, for carrying out the above stated 85 objects and such other objects as will appear from the following description of certain preferred embodiments illustrated in the accompanying drawings wherein:

Fig. 1 is a side elevation of apparatus embodying the principles of my invention.

Fig. 2 is an end elevation of the apparatus, certain parts being shown in section.

Fig. 3 is an enlarged sectional view of the apparatus showing the course traveled by 90 the blocks in passing through the apparatus.

Figs. 4, 5, 6 and 7 are sectional detail views taken on the lines 4—4, 5—5, 6—6 and 7—7 respectively of Fig. 3.

Fig. 8 is a detailed view showing the 100 means employed for preventing a block, which has just been pushed out of the dies, from being caught therebetween when they close upon the succeeding block.

Fig. 9 is a face view of one of the dies 105 shown in Fig. 8.

Fig. 10 is a sectional view taken on line 10—10 of Fig. 9.

Fig. 11 is a perspective view of a block after having passed through the necessary planing and sawing operations hereinbefore referred to.

5 Fig. 12 is a perspective view of the block after having passed through the first set of rollers showing four of the transverse edges rounded.

10 Fig. 13 is a perspective view of the block after having passed through the second set of rollers, showing the remaining four transverse edges rounded.

15 Fig. 14 is a perspective view of the block after having passed through the die for rounding the corners thereof.

20 Fig. 15 is a face view of a modified form of die designed to eliminate the sharp edges and corners on a block in one operation, and

25 Fig. 16 is a perspective view of the finished block in the die shown in Fig. 15.

Like characters of reference designate like parts in the several views.

30 After the blocks have been preliminarily operated upon as hereinbefore described, they are inspected and placed by hand on a conveyor belt 20 operating over a table 20^a, care being taken to place the blocks so that the grain thereof runs transversely of the belt. The blocks are delivered by the 35 belt 20 into a vertical chute 21 through which they drop by gravity into the path of a horizontally arranged plunger 22 secured to a cross-head 23 slidably mounted on horizontal guide rods 24 which are secured to the framework of the apparatus. The blocks are pushed by the plunger 22 one by one through the set of rollers designated generally by the reference numeral 25 and into the path of a vertically arranged plunger 40 26 secured to a cross-head 27 slidably mounted on vertical guide rods 28 also secured to the framework of the apparatus. The plunger 26 forces the blocks one by one through a second set of rollers designated 45 generally by the reference numeral 29 and into a vertical passageway 30 through which they pass by gravity into the path of another horizontally arranged plunger 31 which is attached to the cross-head 23. The 50 plunger 31 forces the blocks one by one into position between the dies 32 and 33 which are operated by a toggle arrangement designated generally by the reference numeral 34. The blocks are pushed from between the dies 55 32 and 33 into a horizontal passageway 35 (Fig. 8) from which they may be delivered to a suitable conveyor (not shown).

50 The drive shaft 36 of the apparatus may be connected directly to a source of power (not shown) by a pulley 37 or driven from a shaft 38 of an associated machine (not shown), for example, a machine for printing matter on the blocks, by the spiral gears 39 and 40. A power wheel 41 is secured to 60 the shaft 36 to which the cross-heads 23

and 27 are connected by the respective links 42 and 43. A bell crank 44 is pivoted at 45 to the framework of the apparatus, the horizontal arm 46 of which is connected by links 47 to the toggle arrangement 34. The lower 70 end of the vertical arm 48 of the bell crank projects into a socket 49 formed in the cross-head 23. The arms 50 of the toggle are pivoted at 51 to a stationary part 52 of the framework, and are each provided with a 75 tooth 53 which meshes, respectively, with the teeth 54 of the horizontally sliding members 55.

80 The dies 32 and 33 shown in detail in Figs. 8 to 10 are secured to the sliding members 55 by screws 56, these dies being formed with annular concave surfaces 32^a and 33^a respectively which are adapted to bear upon, compress and round the eight corners of the block when it is positioned between them 85 and they are moved toward each other by the toggle arrangement. In Fig. 8 I have shown means to cause a block which has just been pushed from between the dies to assume a position whereby it will not be caught 90 therebetween when they close upon the succeeding block. The die 33 is chamfered or beveled at 57 and the die 32 is chamfered or beveled at 58, as shown, the surface 58 being at a sharper angle relative to the plane 95 of the dies than that of the surface 57. The left hand side of the passageway 35 is cut away at 59 to permit the block to be pushed sidewise. The block 60 is pushed from between the dies by the succeeding block 61 100 and as the dies close upon the block 61 the surface 58, since it is at a sharper angle relative to the plane of the dies than the surface 57, engages and pushes the block 60 into the position shown.

105 The roller sets 25 and 29 are identical in construction and are illustrated in detail in Figs. 4 to 6. Each set preferably comprises two pairs of rollers 62 which are mounted on bolts 63 secured in parallel arrangement in bearing blocks 64 adjustably mounted on plates 65. The rollers are provided with horizontal portions 66 adapted to bear upon the top or bottom of a block, and with flange portions 67 adapted to bear 110 against the sides of the block. The circumferential corners between the horizontal and flanged portions are billeted to provide a concave surface 68 adapted to bear upon the edges of the block whereby the sharp edges 115 of the block are eliminated by being compressed and rounded. The bearing blocks 64 are provided with perforations 69 adapted to receive the bolts 63 and with threaded recesses 70 adapted to receive 120 the screws 71 which extend through radial slots 72 formed in the plates 65. By adjusting the relative positions of the screws 71 in the slots and tightening or 125 loosening the nuts on the bolts 63 the dis- 130

tance between the rollers may be changed to accommodate blocks of different sizes. The bearing blocks on adjacent ends are preferably provided with lugs 73 perforated 5 for the reception of cap screws 74. The bolts 63 cooperating with the screws 71 effectively prevent the rollers of one pair from spreading apart and the screws 74 also cooperating with the screws 71 effectively 10 prevent the opposing pairs of rollers from spreading apart. A spring 75 may be interposed between the rollers of each pair to normally hold them against the adjacent bearing blocks.

15 The various passageways through which the blocks travel in passing through the apparatus are substantially identical in construction and are preferably made adjustable to accommodate blocks of different sizes. The construction employed, for example, is illustrated in detail in Fig. 7. The side members 76 and 77 are adjustably mounted on threaded studs 78 secured to the framework of the apparatus. The passageway is completed by mounting the guide strips 79 on the studs 78 between the side members 76 and 77. The strips 79 are provided with transversely extending slots 80 which permit the necessary vertical adjustments to be made to accommodate the passageway to blocks of different sizes. A relatively stiff spring 81 is interposed between the strips 79 which in cooperation with the nuts 82 on the studs 78 permits lateral adjustments of the side members 76 and 77. Each set of rollers is provided with strips 83 to guide the blocks as they are forced through between the rollers. These strips are secured to angle brackets 84, which are secured to the plate 65, by screws 85, each bracket having a slot 86 which permits the necessary relative adjustments to accommodate blocks of different sizes. The plates 65 are slidably mounted in V-shaped grooves 87 formed in the framework and are secured therein by the set screws 88, this arrangement permitting convenient removal of the plates and free access to the various devices attached thereto when it is desired 50 to make adjustments.

Operation.

The blocks are fed into the machine by placing them on the conveyor belt 20 with 55 the edge of the grain running transversely thereon. They pass down the passageway 21 into the path of the plunger 22 and are forced horizontally through the first set of rollers whereby the four horizontal, transverse grained, sharp edges are compressed and rounded. They are then pushed one by one into the path of the plunger 26 and are forced vertically through the second set of rollers whereby the four vertical, 60 transverse grained, sharp edges are com-

pressed and rounded, the plane of the rollers of one set being at substantially right angles to that of the other. After leaving the second set of rollers they fall into the path of the plunger 31 and are thereby 70 pushed into position between the dies 32 and 33 which grip the block by its eight corners and further compress and round the same. Assuming the power wheel 41 is in the position shown in Fig. 1, when it 75 moves 90 degrees in the direction of the arrow the plunger 22 and the cross head 23 will be at the end of their forward excursion. When the cross head is in this position the arm 46 of the bell crank 44 is 80 in its highest position with the result that the dies 32 and 33 are in their extreme open position which permits a block to be moved therebetween by the plunger 31. The plunger 26 will have traveled downward and be just over the block which will have been forced through the first set of rollers by the plunger 22. As the power wheel moves 90 degrees farther the plunger 26 travels to 85 the end of its downward excursion forcing the blocks through the second set of rollers. A further 90 degree movement of the power wheel brings the cross head 23 to the end of its return excursion with the result that the dies are brought to bear upon the corners of the block therebetween and the plungers 22 and 31 are withdrawn sufficiently to permit the blocks from the respective passageways 21 and 30 to drop in front 90 of them ready to be pushed forward on the 100 next forward excursion.

In Fig. 11 I have shown a block as it is fed to the machine, the four longitudinal or straight grain sharp edges *a*, *a* having been eliminated by the preliminary planing operation. In Fig. 12 I have shown the block after it has been passed through the first set of rollers the four horizontal sharp transverse grain edges *b*, *b*, having been eliminated. In Fig. 13 I have shown the block 105 after it has been passed through the second set of rollers, the remaining four vertical sharp transverse grain edges *c*, *c*, having been eliminated. In Fig. 14 I have shown the block after it has been subjected to the 110 action of the dies, the four corners *d*, *d*, having been further compressed and rounded.

In Figs. 15 and 16 I have shown one of a pair of dies 89 adapted to eliminate the sharp edges and corners on a block in one operation, making it unnecessary to pass the blocks through the two sets of rollers. These dies are each formed with a square recess 90, the corners between the bottom of the recess and its walls being billeted to provide 115 concave bearing surfaces 91 adapted to bear upon the sharp edges and corners of a block placed therebetween when the dies are moved toward each other. These dies may be secured to a toggle arrangement and the blocks 120 125 130

pushed into position therebetween by mechanism operating in the manner of that shown in the preceding figures. The blocks are passed through the preliminary operations described to eliminate the sharp longitudinal grain edges and are then positioned between the dies with the transverse grain faces toward the dies, whereupon the eight sharp transverse grain edges and corners are 10 compressed and rounded when the surfaces 91 are brought to bear upon these edges and corners.

It will be obvious that modifications of various kinds may be made in the constructions, arrangements and devices without departing from the principles of my invention. I do not limit the invention therefore to the constructions, arrangements and devices herein described except only in so 20 far as certain of the appended claims are specifically so limited.

I claim:

1. The method of eliminating sharp edges on a block which comprises passing the 25 block successively through sets of rollers adapted to compress its edges with non-parallel faces of the block successively in the lead.

2. The method of eliminating sharp edges 30 on a block which comprises passing the block successively through sets of rollers adapted to compress its edges with non-parallel faces of the block successively in the lead, and then passing the block between 35 pressure applying parts for further rounding the corners.

3. Method of eliminating sharp edges on 40 a block of the class described which consists in taking a block which has been preliminarily operated upon to round two parallel edges on two opposite sides, and passing it through one set of rollers and then at substantially right angles through another set of rollers, said rollers being adapted to 45 bear upon the edges of the block, whereby the eight remaining edges thereof are compressed and rounded.

4. Method of eliminating sharp edges on 50 a block of the class described which consists in taking a block which has been preliminarily operated upon to round its four straight grain edges, and passing it through one set of rollers and then at substantially right angles through another set of rollers, 55 said rollers being adapted to bear upon the edges of the block whereby the transverse grain edges are compressed and rounded.

5. Method of eliminating sharp edges on 60 a block of the class described which consists in taking a block which has been preliminarily operated upon to round its four straight grain edges, and passing it horizontally through one set of rollers and then vertically through another set of rollers, 65 said rollers being adapted to bear upon

the edges of the block, whereby the transverse grain edges are compressed and rounded.

6. Method of eliminating sharp edges and 70 corners on a block of the class described which consists in taking a block which has been preliminarily operated upon to round its four straight grain edges, passing it through one set of rollers and then at substantially right angles through another set 75 of rollers, said rollers being adapted to bear upon the edges of the block, whereby the transverse grain edges are compressed and rounded, and then gripping and squeezing the eight corners of the block between dies 80 to further round the corners.

7. Method of eliminating sharp edges and 85 corners on a block of the class described which consists in taking a block which has been preliminarily operated upon to round its four straight grain edges, passing it horizontally through one set of rollers and then vertically through another set of rollers, 90 said rollers being adapted to bear upon the edges of the block, whereby the transverse grain edges are compressed and rounded, and then gripping and squeezing the eight corners of the block between dies to further round the corners.

8. Method of eliminating the sharp edges 95 on a block of the class described which consists in taking a block which has been preliminarily operated upon to round two parallel edges on two opposite sides, and gripping and squeezing the eight remaining 100 edges thereof between two dies thereby rounding those edges.

9. Method of eliminating the sharp edges 105 on a block of the class described which consists in taking a block which has been preliminarily operated upon to round its four straight grain edges, and gripping and squeezing the eight transverse grain edges between two dies thereby rounding those 110 edges.

10. Apparatus for eliminating sharp edges on blocks of the class described comprising a plurality of rollers arranged in sets and adapted to bear upon the edges of the blocks as they are passed between the rollers thereby compressing and rounding the same, each successive set of rollers being at substantially right angles to the preceding set of rollers, and means to convey the blocks through the successive sets of rollers without turning the blocks and with different faces of the blocks successively in the lead.

11. Apparatus for eliminating sharp edges 115 and corners on blocks of the class described comprising a plurality of rollers arranged in sets and adapted to bear upon the edges and corners of the blocks as they are passed between the rollers thereby compressing and rounding the same, each successive set of rollers being at substantially right angles 125 130

- to the preceding set of rollers, means for conveying the blocks through the successive sets of rollers without turning the blocks and with different faces of the blocks successively in the lead, dies adapted to bear upon the corners of the blocks and further compress and round the same, and means to convey the blocks from the last set of rollers and position them between the dies. 5 70
- 10 12. Apparatus for eliminating sharp edges on blocks of the class described which have been preliminarily operated upon to round two parallel edges on opposite sides comprising a plurality of rollers arranged in two sets and adapted to bear upon the sharp edges of the blocks as they are passed between the rollers thereby compressing and rounding the same, one set of rollers being in a vertical and the other in a horizontal plane, and means to force the blocks horizontally into one set and then without turning the blocks to force them vertically through the other set of rollers. 15 80
13. Apparatus for eliminating sharp edges and corners on blocks of the class described which have been preliminarily operated upon to round two parallel edges on opposite sides, comprising a plurality of rollers arranged in two sets and adapted to bear upon the sharp edges and corners of the blocks as they are passed between the rollers thereby compressing and rounding the same, dies adapted to bear upon the corners of the blocks and further compress and round the same, and means to convey the blocks successively between the two sets of rollers with non-parallel faces successively in the lead and then to position the blocks between the dies. 25 90
- 40 14. Apparatus for eliminating sharp edges on blocks of the class described comprising a plurality of rollers arranged in sets and adapted to bear upon the edges of the blocks as they are passed between them thereby compressing and rounding the same, plungers adapted to force the blocks between the rollers of each set, and means connecting said plungers to a source of power. 45 100
15. Apparatus for eliminating sharp edges on blocks of the class described comprising a plurality of rollers arranged in sets and adapted to bear upon the edges of the blocks as they are passed between them thereby compressing and rounding the same, reciprocating plungers adapted to force the blocks between the rollers of each set, and means connecting said plungers to a source of power. 50 110
- 60 16. Apparatus for eliminating sharp edges on blocks of the class described comprising a plurality of rollers arranged in sets and adapted to bear upon the edges of the blocks as they are passed between them, thereby compressing and rounding the same, each successive set of rollers being at substantially right angles to the preceding set, plungers adapted to force the blocks between the rollers of each set, and means connecting said plungers to a source of power. 65 120
17. Apparatus for eliminating sharp edges on blocks of the class described which have been preliminarily operated upon to round two parallel edges on opposite sides comprising a plurality of rollers arranged in two sets and adapted to bear upon the sharp edges of the blocks as they are passed between them, thereby compressing and rounding the same, plungers adapted to force the blocks between the rollers of each set, and means connecting said plungers to a source of power. 70 130
18. Apparatus for eliminating sharp edges on blocks of the class described which have been preliminarily operated upon to round the four straight grain edges comprising a plurality of rollers arranged in two sets and adapted to bear upon the edges of the blocks as they are passed between them, thereby compressing and rounding the same, one set of rollers being in a vertical and the other in a horizontal plane, plungers adapted to force the blocks between the rollers of each set, and means connecting said plungers to a source of power. 75 135
19. Apparatus for eliminating sharp edges on blocks of the class described comprising a plurality of rollers arranged in sets and adapted to bear upon the edges of the blocks as they are passed between them thereby compressing and rounding the same, a plunger associated with each set, the plunger of each set being at an angle to the line of travel of the block through the next preceding set and means connecting said plungers to a source of power, whereby the plungers are reciprocated and the blocks pushed one by one through the several sets of rollers with non-parallel faces leading. 80 140
20. Apparatus for eliminating sharp edges on blocks of the class described comprising a plurality of rollers arranged in sets and adapted to bear upon the edges of the blocks as they are passed between them thereby compressing and rounding the same, a reciprocating cross head associated with each set of rollers, a plunger secured to each of said cross heads, and means connecting said cross heads to a source of power, said plungers being positioned at right angles to each other whereby the blocks are advanced by the several plungers with non-parallel faces leading. 85 145
21. Apparatus for eliminating sharp edges on blocks of the class described comprising a plurality of rollers arranged in sets and adapted to bear upon the edges of the blocks as they are passed between them thereby compressing and rounding the same, guiding means for the blocks associated with the sets of rollers. 90 150

ciated with each set of rollers, plungers movable at an angle to each other associated with said guiding means, and means connecting said plungers to a source of power whereby the plungers are reciprocated and the blocks pushed through the several sets of rollers with non-parallel faces leading.

22. Apparatus for eliminating sharp edges on blocks of the class described comprising a plurality of rollers arranged in sets and adapted to bear upon the edges of the blocks as they are passed between them thereby compressing and rounding the same, guiding means for the blocks associated with each set of rollers, plungers movable at an angle to each other associated with said guiding means, and means connecting said plungers to a source of power whereby the plungers are reciprocated and the blocks pushed through the several sets of rollers with non-parallel faces leading, the rollers of each set and said guiding means being adjustable to accommodate blocks of different sizes.

23. Apparatus for eliminating sharp edges and corners on blocks of the class described comprising a plurality of rollers arranged in sets at an angle to each other and adapted to bear upon the edges and corners as the blocks are passed between them thereby compressing and rounding the same, dies adapted to bear upon the corners of the blocks and further compress and round the same, a plunger associated with each set of rollers and said dies, and means connecting said plungers to a source of power whereby the plungers force the blocks between the rollers of each set with non-parallel faces in the lead and position them between the dies.

24. Apparatus for eliminating sharp edges and corners on blocks of the class described comprising a plurality of rollers arranged in sets at an angle to each other and adapted to bear upon the edges and corners as the blocks are passed between them thereby compressing and rounding the same, dies adapted to bear upon the corners of the blocks and further compress and round the same, a reciprocating plunger associated with each set of rollers and said dies, and means connecting said plungers to a source of power whereby the plungers force the blocks between the rollers of each set with non-parallel faces in the lead and position them between the dies.

25. Apparatus for eliminating sharp edges and corners on blocks of the class described comprising a plurality of rollers arranged in sets at an angle to each other and adapted to bear upon the edges and corners as the blocks are passed between them thereby compressing and rounding the same, dies adapted to bear upon the corners of the blocks and further compress and round the

same, means adapted to open and close said dies, a plunger associated with each set of rollers and dies, and means connecting said die controlling means and said plungers to a source of power whereby the plungers force the blocks between the rollers of each set with non-parallel faces successively in the lead and position them between the guides.

26. Apparatus for eliminating sharp edges on blocks of the class described which have been preliminarily operated upon to round two parallel edges on opposite sides comprising a plurality of rollers arranged in two sets at right angles to each other and adapted to bear upon the sharp edges of the block as they are passed between the rollers thereby compressing and rounding the same, dies adapted to bear upon the corners of the blocks and further compress and round the same, means adapted to open and close said dies, a cross head associated with each set of rollers, means connecting said cross heads with a source of power, means connecting said die controlling means with one of said cross heads, and means associated with said cross head whereby the blocks are forced between the rollers of each set with non-parallel faces successively in the lead and positioned between the dies.

27. Apparatus for eliminating sharp edges and corners on blocks of the class described which have been preliminarily operated upon to round two parallel edges on opposite sides comprising a plurality of rollers arranged in two sets and adapted to bear upon the sharp edges of the blocks as they are passed between the rollers thereby compressing and rounding the same, one set of rollers being in a vertical plane and the other in a horizontal plane, dies adapted to bear upon the corners of the blocks and further compress and round the same, means adapted to open and close said dies, horizontally and vertically operating cross heads associated with the respective sets of rollers, means connecting said cross-heads with a source of power, means connecting said die controlling means with the horizontally operating cross-head, and means associated with said crossheads whereby the blocks are forced between the rollers of each set and positioned between the dies.

28. In apparatus of the class described the combination of a pair of dies each having concave surfaces adapted to bear upon the corners of blocks of the class described, means adapted to open and close said dies, means adapted to position the blocks one by one between said dies, and means adapted to cause a block which has been pushed from between the dies to assume a position whereby it will not be caught therebetween when they close upon the succeeding block.

29. In apparatus of the class described the

combination of a pair of dies each having concave surfaces adapted to bear upon the corners of blocks of the class described, means adapted to open and close said dies, 5 means adapted to position the blocks one by one between said dies, and means associated with said dies adapted to cause a block which has been pushed from between the dies to assume a position whereby it will not 10 be caught therebetween when they close upon the succeeding block.

30. In apparatus of the class described the combination of a pair of dies each having concave surfaces adapted to bear upon the 15 corners of blocks of the class described, means adapted to open and close said dies and means adapted to position the blocks one by one between said dies, said dies being chamfered to provide bearing surfaces one 20 of which is of greater angularity than the other relative to the plane of the dies for the purpose described.

31. Apparatus of the class described comprising a pair of dies having concave surfaces adapted to bear upon the corners of 25 blocks of the class described, a toggle arrangement associated with said dies and adapted to open and close the same, a reciprocating member, a bell crank one arm of 30 which is connected to said toggle arrangement and the other to said reciprocating member, and means associated with said reciprocating member adapted to position the blocks between the dies.

35. 32. In apparatus of the class described, the combination of a supporting member, a pair of rollers mounted thereon, said rollers having concave surfaces in spaced relation adapted to bear upon the sharp edges of a 40 block of the class described when it is passed between them, and means positioned between the concave surfaces of said rollers for guiding the block between the rollers.

33. In apparatus of the class described 45 the combination of a supporting member, a pair of bolts parallelly mounted thereon, a pair of rollers mounted on each of said bolts, said rollers having surfaces adapted to bear upon the sharp edges of a block of 50 the class described when it is passed between them for applying pressure to said edges, and means associated with said supporting member and located between the several pairs of rollers adapted to guide the blocks therebetween.

34. In apparatus of the class described the combination of a supporting member, a pair of bolts parallelly mounted thereon, a pair of rollers on each bolt having concave surfaces adapted to bear on the sharp edges of a block of the class described when it is passed between them, and means whereby the distances between the bearing surfaces of the rollers on each bolt and between the 60 bearing surfaces of the rollers on the two

bolts may be changed to accommodate blocks of different sizes.

35. In apparatus of the class described the combination of a supporting member having radial slots formed therein, bearing 70 blocks secured to said member by means slideable in said slots, a pair of bolts mounted in said block, and a pair of rollers mounted on each of said bolts having surfaces adapted to bear upon the sharp edges of a block of the class described when it is passed 75 between them.

36. In apparatus of the class described the combination of a supporting member having radial slots formed therein, bearing 80 blocks secured to said member by means slideable in certain of said slots, a pair of bolts mounted in said blocks, a pair of rollers mounted on each of said bolts having surfaces adapted to bear upon the sharp edges 85 of a block of the class described when it is passed between them, brackets secured to said member by means slideable in the other slots, and guide members secured to said brackets.

37. In apparatus of the class described the combination of a supporting member having radial slots formed therein, bearing blocks secured to said member by means slideable in said slots, a pair of bolts extending longitudinally of said member and mounted in said blocks, a pair of rollers mounted on each of said bolts having surfaces adapted to bear upon the sharp edges 95 of a block of the class described when it is passed between them, and means adapted to hold said bearing blocks against spreading apart transversely.

38. Apparatus of the class described comprising a plurality of rollers arranged in sets, each set being mounted adjustably with respect to each other on a supporting member which is slidably mounted in the apparatus, said rollers having surfaces adapted to bear upon the edges of the blocks as they are passed between the rollers thereby compressing and rounding the same, and means adapted to force the blocks between the rollers.

39. Apparatus of the class described, comprising a plurality of rollers arranged in sets, the rollers of each set being mounted adjustably with respect to each other on a supporting member, said rollers having surfaces adapted to bear on the sharp edges of a block of the class described when it is passed between them, guiding members adapted to guide the blocks to and from each set of rollers, and means to force the blocks through each set of rollers, said guiding members being adjustable relative to each other whereby blocks of different sizes may be accommodated.
